SUSPENSION FOR CABINET IRONERS

Allan L. Briggs, Jamestown, N. Y., assignor to
 Jamestown Metal Equipment Company, Inc.,
 Jamestown, N. Y., a corporation of New York

Application November 14, 1946, Serial No. 709,672

2 Claims. (Cl. 312—27)

1

This invention relates to a cabinet type ironing machine and more particularly to means for supporting an ironer in such a manner as to render it movable into position of rest within the cabinet, or position of use adjacent thereto.

One of the more important objects and advantages of the invention lies in the provision of an ironer cabinet having a permanent, fixed top that may serve as a conventional shelf or table at any time, whether or not the ironer is stored within the cabinet, or withdrawn therefrom for use.

Another object of the invention lies in the provision of a cabinet having a front opening through which an ironer is moved either into position of storage or use.

Another important object of the invention lies in the provision of a cabinet having an ironer supporting mechanism that is capable of sustaining an ironer in an exterior proximate position with respect to the cabinet, or an interior storage position.

It is also an important object of the invention to provide a mechanism that, in all positions of an ironer, the weight thereof will be substantially counterbalanced in order that an operator need exert little or no force in moving the ironer from one to another of its extreme positions.

It is further considered to be an important object and advantage of the invention to provide an ironer carrying mechanism that will locate an ironer in position of use directly in front of the cabinet opening, and at such height that the top of the cabinet may serve as a convenient place of at least temporary storage for ironed articles.

Another important object of the invention is to provide an ironer carrying mechanism that is capable of storing the ironer in an inclined endwise position, thereby facilitating use of a comparatively shallow and narrow storage cabinet.

Other objects and advantages of the invention will be more fully understood from a consideration of the following specification, taken in conjunction with the accompanying drawing; and in which

Fig. 1 is a front elevational view of an ironer cabinet in which is embodied one form of the invention;

Fig. 2 is a side elevational view of the cabinet, a substantial portion of the side wall being broken away to disclose the position of the ironer and its supporting mechanism when the ironer is in

position of storage, this view being taken substantially as suggested by the line 2—2 of Fig. 1;

Fig. 3 is a fragmentary view, partly in section, showing the position of certain of the movable parts of the ironer supporting mechanism when the ironer has been partially withdrawn from the cabinet, being taken on the line 3—3 of Fig. 9;

Fig. 4 is a view similar to Fig. 2, showing the ironer supporting mechanism fully extended and the ironer withdrawn from the cabinet into operative position;

Fig. 5 is an enlarged fragmentary vertical sectional view of a portion of the latching mechanism, being taken substantially on the line 5—5 of Fig. 2;

Fig. 6 is an enlarged fragmentary vertical sectional view of a part of the ironer support, being taken substantially on the line 6—6 of Fig. 2;

Fig. 7 is an enlarged sectional view of a further detail of the ironer supporting mechanism, being taken substantially on the line 7—7 of Fig. 2;

Fig. 8 is an enlarged fragmentary sectional view showing a part of the pivotal connection of the mechanism with the ironer base, being taken substantially on the line 8—8 of Fig. 2;

Fig. 9 is a top plan view of the ironer supporting structure, when the parts thereof are in the position shown in Fig. 2, the view being taken substantially as indicated on the line 9—9 of this figure;

Fig. 10 is an enlarged vertical fragmentary sectional view of the ironer support latch mechanism, being taken substantially on the line 10—10 of Fig. 9;

Fig. 11 is an enlarged vertical sectional view of a part of the supporting mechanism, the parts being shown in full line as in Fig. 2, and in phantom with the ironer in the position shown in Fig. 4;

Fig. 12 is a detail of the counterbalance, being taken substantially on the line 12—12 of Fig. 11;

Fig. 13 is an enlarged detail, partly in section, of a part of the linkage of the ironer support, being taken substantially on the line 13—13 of Fig. 11; and

Figs. 14 and 15 are enlarged fragmentary details taken substantially on the lines 14 and 15 of Fig. 11.

Referring more particularly to the drawing, the reference numeral 10 is employed to generally designate a cabinet in which one modification of an ironer suspension embodying the invention is provided. The cabinet includes a base 11 which may be of somewhat less depth than the cabinet proper to provide toe space 12, this space

enabling convenient use of the cabinet as a conventional shelf when the ironer has been moved into a position of storage within the cabinet. Mounted on the base 11 is the cabinet proper which includes a rear wall 13 and side walls 14. At its front, marginal panels 16 define an opening adapted to be closed by a horizontally swinging door 17. A top 18 is permanently joined to the side and rear walls in any suitable manner. The side and rear walls of the cabinet are of a height to locate the top 18 at the conventional table or kitchen shelf height and, consequently, the top of the cabinet may at all times be used as a shelf, regardless of whether the ironer is in position of use or storage.

One type of ironer adapted to be mounted in the cabinet is generally indicated by the reference numeral 19, and includes a base 21 that is permanently secured in any suitable manner to a shelf 22. This shelf, both for appearance and strength, is formed with depending marginal flanges 23. It will be noted, however, that towards the rear, the sides of the shelf are recessed as indicated at 24. Substantially midway of the side flanges of the shelf, the lower ends of a pair of suspension arms 26 are attached. This attachment takes the form of a pivotal structure of the type shown in Fig. 8, wherein a bolt 27 projects through the arm 26 and flange 23 and is secured against displacement by a nut 28. Adjacent the rear of the sides of the shelf, and attached to the flanges 23 in the recesses 24, are further suspension arms 29. The structure by which these arms are attached to the shelf may be identical with that shown in Fig. 3. It is to be observed that, since the arms 29 are set into the recesses 24, they are offset inwardly of the path of travel of the arms 26 and, thus, during movement of the ironer from one position to another, these arms may assume an overlapping or overlying position such, for example, as suggested in Fig. 4.

Adjacent the top of the cabinet are supporting rails 31. These rails, as may be seen in Fig. 9, extend from the rear wall 13 to the panels 16, and are spaced from their respective side walls 14 substantially the width of the panels 16. Near the forward end of the vertical flange 32, each rail is formed with a horizontally extending slot 33, the forward end of which is formed with a notch 34. Suitable brackets 36 are attached to the rear wall 13 somewhat beneath, but in the same vertical plane with rails 31. These brackets serve to mount corresponding ends of a pair of inclined rails 37. The rails 37 each include horizontal and vertical flanges 38 and 39. The forward ends of flanges 39 are permanently joined to the vertical flanges 32 of the rails 31 at substantially the point suggested in the drawing.

The upper ends of suspension arms 26 are mounted on a rod 41 which extends between and is carried by rails 31. Suitable collars 42 serve to locate the ends of these arms in spaced relationship to the inclined rails 37 (see Fig. 6). The upper ends of arms 29 are mounted on a further rod 43 which extends between and is carried by rails 31. It will be noted that rod 43 is located toward the rear of the rails 31, whereas rod 41 is located at the point of jointure of rails 37 and 31; in fact, the ends of rod 41 being shown as projecting through the flanges 38 of the rails 37. Since arms 26 and 29 are, at their place of attachment to the shelf 22, relatively, laterally offset, and it is desired that these arms, at least in part, have overlapping relationship during cer-

tain operation of the device, suitable collars 44 are mounted on rod 43 to predetermine the plane of movement or arms 29 with respect to the shelf 22 and arms 26.

Corresponding ends of links 46 are attached to the suspension arms 26, adjacent their pivotal connection with rod 41. The other ends of these links mount pins 47 which project into the slots 33 and are movable therealong. From the drawing it is evident that the swinging movement of arms 26 about their pivotal connection with rod 41 is limited to the extent of movement of pins 47 in slots 33. Further links 48 are pivotally joined at corresponding ends with arms 26, the location of these links being substantially as indicated in the drawing. The other end of each link 48 pivotally connects with one end of a short arm 49. The other end of each arm 49 is pivotally joined, as at 51, to the vertical flange 39 of the inclined rail 37 (see Figs. 3, 12 and 14). Adjacent the pivotal connection 51, each arm 49 pivotally mounts corresponding ends of a pair of links 52 and 52a. The other ends of these links are joined to a pin 53 which extends through a slot 54 in the flange 39 of rail 37 and mounts a cap 56 through which an eye-bolt 57 projects. The threaded end of this bolt receives a nut 58, whereas the eye of the bolt is engaged with one end 59 of an expansion spring 61. The other end 62 of this spring is attached to a fixed pin 63, carried by flange 39 of rail 37.

To secure the ironer 19 in its position of use, the structure shown in Figs. 9 and 10 is provided. A bar 64 extends across the front of the cabinet and projects through and beyond the vertical flanges 32 of rails 31. Attached at approximately the bar's ends are straps 66. The free end of each strap is curved, as at 67, and is adapted to contact pin 47 in its forward position when bar 64 is rotated. On the front panel 16, adjacent the free edge of the door 17, is a bracket 68 that serves to mount a release knob 69. A suitable spring 71, located in a housing 72, normally urges the knob into the position shown in Fig. 10. An end 73 of the knob, projecting beyond the housing 72, is adapted to contact a strap 74 which is also attached to bar 64 (see Fig. 9). When the ironer has been moved to the position shown in Fig. 4, the shanks of pins 47 drop into notches 34 of slots 33. The ends of these pins, in this position, lie against the ends 67 of the latch straps 66. Of course, the weight of the ironer, as applied through links 46, prevents inadvertent displacement of pins 47 from their position in notches 34. When it is desired to return the ironer to its place of storage, the release knob 69 is depressed and the end 73 thereof swings strap 74, thereby rotating bar 64 and causing straps 66 to lift pins 47 out of the notches 34.

To more fully appreciate the structure of the invention, a complete operating cycle is set out as follows: When it is desired to withdraw the ironer 19 from the position of Fig. 2 to that of Fig. 4, the door 17 is swung open at least to the position shown. A handle 76, attached to the front flange 23 of the shelf 22, provides a convenient means for withdrawing the ironer. When the operator pulls outwardly on the handle, the ironer swings forwardly and upwardly, traveling through a path defined by the length, angularity, and position of attachment therewith of suspension arms 26 and 29. Withdrawal of the ironer from a lower to an upper position requires little effort on the part of the operator inasmuch as the springs 61, in their effort to

contract from an expanded position, supply a considerable part of the force needed to swing the ironer from the position of Fig. 2 almost into the fully extended, elevated position of Fig. 4. As the ironer moves beyond the position of Fig. 3, less effort is required to continue its movement into fully extended position inasmuch as the travel becomes increasingly less upwardly and more outwardly. Thus, as the energy of the springs 61 decreases, the need of such energy also decreases until the point is reached where the springs 61 are fully collapsed and the ironer is in fully extended operative position. As the ironer moves into its fully extended position, pins 47 move into notches 34 and thus prevent the ironer from returning to some intermediate suspended position wherein the springs are sufficiently extended to counterbalance its weight.

Control of the springs 61, as may be observed from the drawing, is provided through the connection of links 52, 52a with the arms 49 and links 48. Through the use of such linkage it is possible to provide springs having sufficient strength to sustain the weight of the ironer even though the expanding travel of these springs is short by comparison with the travel of the ironer suspension arms. By reason of the use of the spring mount shown, it is possible to adjust the spring tension through rotation of nuts 58 to an extent to meet any requirements of the operator. In other words, should it be desired that substantially all effort of moving the ironer into position of use be accomplished through the contracting action of springs 61, nuts 58 may be turned down on the eye-bolts, when the ironer is in extended position, to slightly expand the coils of the springs. Thus, when the ironer is returned to its position within the cabinet, these springs will have greater expansion and, consequently, more fully, if not entirely, sustain the weight of the ironer as it moves into the cabinet.

It will be particularly noted that by reason of the present type of suspension it is possible to house an ironer within a cabinet of comparatively shallow depth. In the present disclosure the cabinet depth is intended to be substantially the depth of standard shelves, cupboards, etc., in order that the front thereof will be in the same vertical plane with other standard kitchen or laundry units. Since the height of the cabinet is the same as conventional kitchen or laundry shelves, the fixed top may readily form a shelf continuation with the tops of other units or permanently installed shelves or cupboards. Inasmuch as the length of the average ironer is greater than the depth of the cabinet shown in the present disclosure, the suspension has been so devised as to tilt the ironer sufficiently to accommodate it within the depth limits of the cabinet. Although the height of the cabinet might be found to be sufficient to accommodate the ironer in an up-ended position, such a storage arrangement places a burden on the operator in moving the ironer to and from its position of storage to an extent far beyond that required by an operator in manipulating an ironer suspended in the manner of the present invention.

Although applicant has shown and described only one modification of a suspension for a cabinet type ironer, it will be understood that modification of certain of the structural details may be made and is contemplated insofar as such modification is within the spirit and scope of the invention as set out in the annexed claims.

Having thus set forth my invention what I claim as new and for which I desire protection by Letters Patent is:

1. A structure of the class described comprising an open front cabinet, a shelf adapted to mount an operative mechanism, said cabinet being of considerably less depth than the overall length 15 of said shelf and said mechanism, arms pivotally connecting the base of said shelf with certain of the interior walls of said cabinet, said arms being adapted to guide said shelf into and out of said cabinet through said open front, said arms 20 having connection with the base of said shelf at such points as to tilt said shelf into an inclined endwise position when in position of storage in said cabinet and means connected with and operable by movement of said arms, said 25 means serving to control the extent of pivotal movement of said arms and determine the storage and use positions of said shelf.

2. A structure of the class described comprising an open front cabinet, a shelf adapted to mount 30 an ironing mechanism, an all purpose suspension for said shelf and mechanism comprising pairs of arms pivotally joined at corresponding ends to said shelf, a pair of rails mounted in and extending substantially from front to rear of 35 said cabinet, the other ends of said arms being pivotally joined to said rails, means for determining the storage and use positions of said shelf operatively joined to said arms, said means including structure adapted to latch said arms 40 in a position to render the mechanism carried by said shelf available for use, operator actuatable means for releasing said latching structure, and counterbalance means associated with said arms 45 in a manner to become increasingly effective to sustain the swingable weight of said shelf and said mechanism when said arms effect movement from a position of use to that of storage within said cabinet.

ALLAN L. BRIGGS.
